UNITED STATES PATENT OFFICE

JAMES G. NOBLE, OF NEW YORK, N. Y.

FASTENING DEVICE

Application filed January 20, 1932. Serial No. 587,803.

This invention relates to a fastening device and has for an object to provide an improved fastening device suitable for quickly fastening the end of a string, cord or similar flexible member, which flexible member may be yieldable or otherwise, and is especially adapted for use in tying packages, parcels, as well as for joining undergarments together.

A further object of this invention is to provide an improved fastening means consisting of a flexible member having one free end and the other end securely attached in a fastening clip.

Still a further object of this invention is to provide a fastening clip which is adapted to permanently receive one end of a flexible member and to detachably yet securely receive the other end of said flexible member after said flexible member has been passed about or through an object it is intended to secure.

With the foregoing and other objects in view, as will hereinafter become apparent, this invention comprises the constructions, combinations and arrangements of parts, hereinafter set forth, disclosed and shown on the accompanying drawings. In these drawings,

Figure 1 is an elevational view of the fastening means showing the fastening clip in perspective detail.

Figure 2 is a side elevational view of the fastening clip of Figure 1 with the yieldable means in fastened position thereon.

Figure 3 is a top edge view of the fastening clip per se.

Figure 4 is an elevational view of the fastening clip with the temporary receiving end bent away, showing how the permanently fixed end of the flexible member is secured thereto,

Figure 5 is a perspective view of the fastening means in operation about a package, and

Figure 6 is a perspective view of the fastening means in operation with a button pad.

There is shown at 10 a flexible means having one end thereof 11 permanently secured in the fastening clip 12. The fastening clip 12 is made of thin sheet metal, preferably brass, tinned steel or other suitable material.

This clip 12 is divided into three folds, an inner fold 13, an adjoining fold 14 and a spaced fold 15. The end 11 of the flexible member is received between the inner fold 13 and the adjoining fold 14, a plurality of indentations 19 being formed on the inner fold 13 in the direction of the adjoining fold 14 so that the end 11 of the yielding member 10 is pinched between the folds 13 and 14 and securely held therein by means of the indentations 19.

As will be observed, the space between the inner fold 13 and the adjoining fold 14 is substantially less than the diameter of the yieldable member 10 whereby the yieldable member 10 will be securely and firmly fastened therein. The spaced fold 15, as will be observed, is folded from the fold 14 about the fold 13, being spaced from the fold 13 a distance approximately equal to or slightly less than the diameter of the yieldable member 10. The joint 16 between the fold 14 and the spaced fold 15 is recessed as at 17, the recess extending a distance somewhat greater than the diameter of the yieldable member 10. Another recess 18 of the same or greater depth is formed in the other end of the fold 15 approximately at the middle of the top edge thereof.

The flexible member 10 may be yieldable or resilient in which case it is not necessary that the clip 12 be of resilient material, although it will be understood that clip 12 may be formed of resilient material, especially if the flexible member 10 is of non-resilient material.

In operation, the flexible member 10 is wrapped around the package 20, as shown in Figure 5, or if desired it may be passed through a pair of loops in adjoining undergarments or passed around any member that it is desired to secure. The end 11 being permanently secured between the folds 13 and 14 freely, end 21 is passed between the folds 15 and 13, through the recess 17 in joint 16, out about the outside of fold 15 and in through the recess 18, where it is again passed between the fold 15 and fold 13, the loose end being allowed to hang freely thereafter.

If the flexible member 10 is of resilient

material, it will be apparent that the member 10 will be stretched somewhat as it is passed about the folds and the inherent resiliency of the member will cause a secure 5 hitch to be formed thereby. If the clip 12 be of resilient material it will be apparent that it would likewise tend to hold the flexible member 10 securely fastened whether or not the flexible member be of resilient material. It is also apparent that even though 10 neither element be of flexible material, it will still be sufficient wedging action formed between end 21 passing through recesses 17 and 18 and again between the folds to supply a secure fastening.

In Figure 6 there is shown a button pad 22 that may be buttoned to an outer shirt (not shown), said button pad serving as the connecting link means to fasten the device to 20 underdrawers (not shown).

The novel features and the operation of this device will be apparent from the foregoing description. While the device has been shown and the structure described in detail, 25 it is obvious that this is not to be considered limited to the exact form disclosed and that changes may be made therein within the scope of what is claimed without departing from the spirit of the invention.

30 Having thus set forth and disclosed the nature of this invention, what is claimed is:

1. A fastening means comprising a clip and a flexible member, said clip being formed of sheet metal in three folds, one end of said 35 flexible member being securely held between two adjacent folds, the third fold being joined to the outer of the first two folds and folded about and spaced from the inner of said first two folds, said clip having a recess 40 formed at one end of the joint between the two outer folds, and a recess formed in the other end of one of said outer folds, whereby the free end of said flexible member may be passed about any desired object and secured 45 by passing between the third fold and said inner fold through the recess in the joint between said outer folds and back through said second recess into the space between said third and inner folds.

50 2. A fastening device comprising a flexible cord and a sheet metal clip, said clip being formed in three folds, two of said folds being pressed firmly together about one end of said flexible member, indentations formed in 55 one of said folds to more securely hold said end of said flexible member permanently therein, the third fold being joined to and spaced from the outer fold and lying adjacent to the inner fold of said first two folds, a recess formed at opposite ends of said third fold, one of said recesses being in alignment 60 with the joint between said third fold and said other outer fold, whereby the free end of said flexible member may be hitched between said third fold and said adjacent fold,

about said third fold through said recesses, and again between said third fold and said adjacent fold.

3. A fastening means comprising a clip and a flexible member, said flexible member being resilient, said clip being formed of sheet metal in three folds, one end of said flexible member being securely held between two adjacent folds, the third fold being joined to the outer of the first two folds and folded about and spaced from the inner of said first two folds, said clip having a recess formed at one end of the joint between the two outer folds, and a recess formed in the other end of one of said outer folds, whereby 70 the free end of said flexible member may be passed about any desired object and secured by passing between the third fold and said inner fold through the recess in the joint between said outer folds and back through said second recess into the space between said third and inner folds.

4. A fastening device comprising a flexible cord and a resilient sheet metal clip, said clip being formed in three folds, two of said 75 folds being pressed firmly together about one end of said flexible member, indentations formed in one of said folds to more securely hold said end of said flexible member permanently therein, the third fold being joined to and spaced from the outer fold and lying adjacent to the inner fold of said first two folds, a recess formed at opposite ends of said third fold, one of said recesses being in alignment with the joint between said third fold and said other outer fold, whereby the free end of said flexible member may be hitched between said third fold and said adjacent fold, about said third fold through 80 said recesses, and again between said third fold and said adjacent fold.

In testimony whereof I affix my signature.
JAMES G. NOBLE.
